D. M. WINANS.
DETACHABLE LIGHT FOR VEHICLE CURTAINS,
APPLICATION FILED DEC. 1, 1917.

1,336,116.

Patented Apr. 6, 1920.

UNITED STATES PATENT OFFICE.

DANIEL M. WINANS, OF BINGHAMTON, NEW YORK, ASSIGNOR TO THE BREWER-TITCHENER CORPORATION, OF BINGHAMTON, NEW YORK, A CORPORATION OF NEW YORK.

DETACHABLE LIGHT FOR VEHICLE-CURTAINS.

1,336,116.

Specification of Letters Patent.

Patented Apr. 6, 1920.

Application filed December 1, 1917. Serial No. 204,945.

To all whom it may concern:

Be it known that I, DANIEL M. WINANS, a citizen of the United States, residing at Binghamton, county of Broome, and State 5 of New York, have invented certain new and useful Improvements in Detachable Lights for Vehicle-Curtains, of which the following is a specification.

The object of the present invention is the 10 provision of an improved "light" or pane holder for the curtain of a vehicle, whereby the light or pane may be readily set or removed, which will securely hold the light to the curtain and prevent rattling or looseness of the parts, whether the pane be of celluloid or of glass.

In carrying out the invention I provide inner and outer pane-holding rings adapted to clamp against opposite sides of the curtain and to hold the edge of the pane, and that portion of the curtain surrounding the pane, between them. One of the rings, preferably the outer one, carries a plurality of nuts which are of novel form and are held 20 by the ring in an improved manner, without the use of solder, removable screws passing through openings in the remaining ring and through holes in the curtain and being engaged with the nuts aforesaid.

The outer ring has a smooth finished appearance and provides a neat and protective border for the pane; the inner ring is neat and discloses only the screw-heads; if of wood, the inner ring and screws may be entirely covered by the inside lining of the curtain.

Preferably the margin of the pane or light will be of just sufficient size to abut, or substantially so, the shanks of the screws 40 where said marginal portion of the pane lies between the inner and the outer rings. The pane is thus held, not only by the clamping action of the rings, but also by the confining action of the screws. By doing away 45 with holes in the marginal portion of the pane, I eliminate the expense of providing such holes and the difficulty encountered in having them register with the screws.

The nuts are held by ears on the ring, said 50 ears being bent down into notched portions of the nuts. While not essential, the notches may be wider than the ears so that the screws will readily find the screw threads in the nuts and the latter will be self-adjust-

ing. This feature facilitates the removal of 55 the parts. The nuts are of peculiar and improved form, their center portions serving as abutments to bear on the curtain, and their notched end portions conforming to the shape of the ring; consequently, the 60 nuts are securely held by the ears and a strong construction is provided.

Preferably both outer and inner rings are arched in cross-section, so that their peripheral edges only bear on the curtain and 65 light; consequently the tension of the screws, which is exerted at the central portions of the inner ring and of the nuts, is distributed through the clamping edges of the rings and the screws can be made very 70 tight without danger of breakage, if a glass pane or light is used.

The embodiments of the invention which are shown in the drawings and hereinafter described are susceptible of modification and 75 are to be considered as illustrative of the invention.

In the accompanying drawings:

Figure 1 is a view looking toward the outside of a curtain provided with the invention, a glass pane being shown;

Fig. 2, is a view looking toward the inside of the curtain;

Fig. 3, is a vertical section through the connecting screws, the inner ring being removed;

Fig. 4, is a view looking toward the inside of the outer ring, certain ones of the ears being shown turned back;

Fig. 5, is a detail view showing the manner of holding the nuts;

Fig. 6, is a detail cross-section through the pane, curtain and pane-holding means;

Fig. 7, is a detail view of a portion of the outer ring showing a pair of the ears;

Fig. 8, is a detail perspective of one of the nuts, and

Fig. 9 is a detail cross section through the pane, curtain, and pane-holding means of a modified form of the invention.

A portion of the curtain of an automobile or other vehicle is shown at 1, and the pane or light at 2. I have illustrated a beveled plate glass pane, but the invention is intended for use in connection with celluloid 105 panes or any transparent pane.

The pane is held by inner and outer rings 3, 4. The present pane 2 being circular, the

rings 3, 4 are annular. I wish it understood, however, that the pane 2 may be elliptical, circular, rectangular, or of any other shape, and that the rings 3, 4 will 5 vary in shape according to the shape of the pane. When calling these elements "rings" in the specification and claim, I do not limit myself to a circular shape, and intend to embrace all shapes to which the invention 10 is adaptable.

The rings 3 and 4 are of metal, preferably stampings. The outer ring 4 is provided with prongs 5 which enter slits 6 in the curtain 1 and are clamped down as 15 shown in Fig. 3, to hold the ring against turning. This outer ring is provided at intervals with ears 7, which are originally in the position shown at 7^a, Fig. 4. These ears are adapted to be bent down as shown at 20 7^b, Figs. 4 and 5, to hold the nuts 8, shown in detail in Figs. 5 and 8. The nuts 8 are of metal, preferably stampings, provided with a raised central portion 8^a which has a screw threaded hole 8^b, and they have end 25 portions 8^c which bear against the inner face of the ring 3 and are provided with notches 8^d adapted to receive the ears 7^b when the latter are bent down. All that is necessary to secure the nuts to the ring 4 is 30 to place them within the ring and bend down the ears 7^b into the notches 8^d. The nuts can neither move within the ring nor become detached from it. I prefer to have the notches 8^d wider than the ears 7^b to permit 35 a slight adjustment so that the nuts will be self-adjusting to enable the screws 9 to readily enter the threaded holes 8^b, but the invention is not limited to this feature.

The screws 9 correspond in number to the 40 nuts 8 and pass through the holes 10 in the inner ring 3, the heads of the screws being preferably countersunk, and their tips 9^a being coned so that they will readily find the screw-threaded openings 8^b. The ring 3, 45 being of metal, will possess some slight resiliency or yield, consequently the screws 9 can be screwed home quite tightly, the pressure being applied to the curtain and the pane at the peripheral edges of the rings 50 3 and 4 without likelihood of damage to the pane 2 if the latter is of glass. The edge of the pane 2 abuts the screws, or substantially so, and thus prevents vertical displacement of the pane.

My invention dispenses entirely with the 55 necessity for soldering or brazing the nuts 8 to the ring 4, thus greatly reducing the expense of manufacturing and eliminating entirely the likelihood of inaccurate spacing of the nuts due to their manner of se- 60 curement.

When a large and heavy bevel plate glass light is used, it may be necessary to more securely fasten it to the curtain 1, the modified inner ring shown in Fig. 9, being particularly adapted for use in that connection. The wooden inner ring 3^a is tacked to the curtain 1, as at 1^a, the screws 9^b are passed through holes in the ring 3^a and into the screw-holes in the nuts 8. A lining 1^b 70 whose edge is clamped between the pane 2^a and the ring 3^a, covers the inner face of the ring and the screw heads.

The ring 3^a being wide and tacked to the curtain, reinforces the latter around the 75 light opening and affords a wide backing for the marginal portion of the heavy light, thus minimizing sagging of the curtain.

My invention is not limited to the use of metal for the rings; and, further, the inner 80 ring may be either exposed or covered.

When the screws are released the pane can be immediately removed and another substituted at the cost of a few minutes time and a substitute pane.

What is claimed is:

Means for securing detachable lights to vehicle curtains comprising rings which are arched in cross-sectional shape, nuts carried by one of said rings, said nuts having raised central portions provided with screw threaded openings and with notched angular end portions bearing against the ring, the said ring having ears received in the arched portions and holding the nuts within the ring, the other ring being provided with openings, and screws having tapered ends, said screws being received in the openings in the last-named ring and passing through the curtain and engaged with the 95 screw threaded openings in the nuts, the screws being located beyond the edge of the light and holding it against vertical displacement, said light and curtain being clamped between the rings.

In testimony whereof, I hereunto affix my signature.

DANIEL M. WINANS.
